[57] **CLAIM**

The ornamental design for a extension for external connection terminals, as shown and described.

DESCRIPTION

FIG. 1 is a top plan view of the extension for external connection terminals of the present invention;

FIG. 2 is a bottom plan view of the extension for external connection terminals of FIG. 1;

FIG. 3 is a left side plan view of the extension of external connection terminals for FIG. 1;

FIG. 4 is a right side plan view of the extension for external connection terminals of FIG. 1;

FIG. 5 is a front plan view of the extension for external connection terminals of FIG. 1; and,

FIG. 6 is a back plan view of the extension for external connection terminals of FIG. 1.

The conductor cord in FIGS. 1, 2, 3 and 4 is shown broken away to indicate an indeterminate length.
